[57] **CLAIM**

The ornamental design for an ampule cuvette, as shown and described.

DESCRIPTION

FIG. 1 is a front elevational view of an ampule cuvette showing my new design, the rear elevational view being a mirror image thereof;

FIG. 2 is a right elevational view of the ampule cuvette of FIG. 1, the left elevational view being a mirror image thereof; and

FIG. 3 is a top plan view thereof.

FIG.1

FIG.2

FIG.3
